UNITED STATES PATENT OFFICE.

ALFRED SWINGLE, OF SAN FRANCISCO, CALIFORNIA.

SEPARATOR OR CLEANER.

SPECIFICATION forming part of Letters Patent No. 350,171, dated October 5, 1886.

Application filed February 24, 1886. Serial No. 193,071. (No model.)

To all whom it may concern:

Be it known that I, ALFRED SWINGLE, of the city and county of San Francisco, State of California, have invented Improvements in Separators or Cleaners; and I hereby declare the following to be a full, clear, and exact description of the same.

My invention relates to a machine which is to be employed for separating or cleaning peas, beans, almonds, &c., after being shelled.

It consists of a box or drum revolving upon a horizontal axis and adapted to receive the shelled peas or other articles in its interior, screening material for separating the larger from the smaller articles or cleaning them from dust or lighter waste matter, and a peculiar cam and its adjuncts, whereby a longitudinal shaking motion may be given to said drum or box.

Referring to the accompanying drawings for a more complete explanation of my invention, Figure 1 is an exterior, partly broken, perspective view of the machine. Fig. 2 is an enlarged view of a section of the cam and the oscillating rollers.

For the shelling of peas or beans and in separating coffee, rice, oats, or other substances from the exterior husks any suitable machine may be used—such as is shown in my patent of March 18, 1884. The peas after being shelled and discharged from the shelling-machine are delivered through a suitable trough or funnel into a rectangular or polygonal box, A, which is supported upon a shaft, C, in a nearly or quite horizontal position. I prefer to fix the arms or supports which extend from the shaft to the sides of the box at points within the box, so as to leave the ends B with unobstructed openings.

For the purpose of separating or sizing the peas or other substances, the sides of the box are made of any suitable screen material, the openings of which being of sufficient size to allow the smaller peas or grains of the substance to be separated to escape, while the larger ones will be retained within the box. The peas or other articles are delivered into the open end of the box through a carrier or chute, D, and the box is caused to rotate slowly upon its shaft. Near its angles, and projecting from its interior surface, are fixed plates E. These plates project at or nearly at right angles from the sides to which they are attached, and serve to

lift the peas or other articles and drop them after the chamber has reached a certain point in its rotation. Similar diagonally-placed lifters, E', act to move the peas or other articles to and fro within the chamber, thus distributing them and separating them so that the smaller ones may readily pass through the screen-surface, while the larger ones will be retained within the box or chamber and eventually be delivered through the opposite end from the one through which they are received.

The box or chamber may be rotated about its longitudinal axis by any suitable gearing or mechanism, which may be connected with the shaft, and it is given a longitudinally-shaking motion by means of a peculiar cam, F. In the present case I have shown this cam as formed upon or fixed to one end of the box or chamber, and its flange travels between two rollers, G. The shafts of these rollers are fixed to the opposite ends of a plate, H, through the center of which a supporting shaft or pin, I, extends. This pin is fixed to some stationary point, so that the rollers G stand upon opposite sides of the flange of the cam, which is thick enough to fit between them. When the box or chamber is rotated upon its longitudinal axis, the flange of the cam traveling between these rollers will give the box a longitudinal reciprocation, the shaft C being so journaled in its boxes, or the chamber so mounted upon the shaft by means of a feather, sliding key, or otherwise as to allow this reciprocation. The movable plate H carries the rollers G, and its oscillations upon its supporting shaft or pin I allow the rollers to adapt themselves to the varying positions of the flange of the cam, so that they will always travel in one direction, and by thus adapting themselves to the varying form of the cam the friction is greatly reduced.

The screen-surface may be made with different sizes of mesh, so as to grade the product, which, falling into a table or receiver below, is conveyed away by chutes K.

Having thus described my invention, what I claim as new, and desire to secure by Letters Patent, is—

1. In a rotary separator or cleaner, the horizontal shaft and the screen box or chamber provided at one end with a serpentine cam, in combination with a stationary spindle and a plate having its center turning upon said sta-

tionary spindle and its ends provided with rollers, which project upon each side of the cam, substantially as herein described.

2. In a separator or cleaner, the combination of a rectangular screen box or chamber provided with the lifting-plates E, projecting from near its angles, and the diagonal distributing-plates E', with the horizontal shaft and means for longitudinally reciprocating said rectangu-

lar screen box or chamber, substantially as described.

In witness whereof I have hereunto set my hand.

ALFRED SWINGLE.
